(57) **CLAIM**

We claim the ornamental design for an electric motorcycle, as shown and described.

DESCRIPTION

FIG. 1 is a top, front, and left side perspective view of an electric motorcycle embodying our new design;

FIG. 2 is a top, rear, and right side perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines in the drawings illustrate portions of the electric motorcycle that form no part of the claimed design.

1 Claim, 7 Drawing Sheets
